AUTOMATIC TELEPHONE DIALER

Ernst A. Eriksson, Lexington, Mass., assignor to Perini
Electronic Corporation, San Mateo, Calif., a corpora-
tion of California

Filed Nov. 23, 1962, Ser. No. 72,589

Term of patent 14 years

(Cl. D26—14)

Fig. 1.

Fig. 2.

Fig. 3.

FIG. 4.

FIG. 5.

FIG. 1 is a view in side elevation of an automatic telephone dialer, embodying my new design;

FIG. 2 is a plan view of the same dialer;

FIG. 3 is a view in side elevation showing the opposite side of the dialer;

FIG. 4 is a view in front elevation of the same; and FIG. 5 is a rear elevation of the same.

I claim:

The ornamental design for an automatic telephone dialer, substantially as shown.
